UNITED STATES PATENT OFFICE.

PAUL I. ANDREWS, OF KENNEBUNK, MAINE.

ROVING-CAN.

1,100,516.

Specification of Letters Patent. Patented June 16, 1914.

Application filed April 11, 1913. Serial No. 760,434.

To all whom it may concern:

Be it known that I, PAUL I. ANDREWS, citizen of the United States, residing at Kennebunk, county of York, State of Maine, have invented a certain new and useful Improvement in Roving-Cans, of which the following is a specification, reference being had therein to the accompanying drawings.

The invention relates to cylindrical cans 10 of fiber and has special reference to cans of that character which are of relatively large size, such as roving cans.

Cans of the character above referred to are subjected to considerable hard usage, and in 15 order to stand the wear and tear and pressure on the rim of the can it is important that the rim should have some sort of reinforcement. It is also desirable that this reinforcement should not project into the interior of the can but that the inner surface 20 should be entirely smooth or free from inwardly projecting portions.

The object of the present invention is to construct the can with a reinforcement of 25 the character above described.

The invention will be fully understood from the following description taken in connection with the accompanying drawings, and the novel features thereof will be pointed 30 out and clearly defined in the claim at the close of this specification.

In the drawings,—Figure 1 is a perspective view of a can embodying the invention. Fig. 2 is a sectional view on a larger scale 35 on line 2—2 of Fig. 1.

The body 1 of the can is preferably of fiber, made in cylindrical form and seamless. The rim is formed with an outwardly extending peripheral roll comprising first 40 an outwardly turned portion 2, thence a downward bend 3, thence a return portion 4 which extends toward the body of the cylinder and preferably into contact therewith, thence an upward turn 5, thence an outward 45 turn 6 between the upper turn 2 and the lower turn 4, forming a substantially horizontal brace which extends from contact with the body 1 into contact with the downward outer bend 3. These last two turns, 5, 50 6, leave the rim without any exposed raw edge. The cylinder being seamless, the curled rim being integral therewith and end-

less, makes a much stronger rim and more capable of resisting crushing lateral pressure or strain than if it were made with an open joint. With this form of construction also no separate core of wire or other material is required within the roll. The inner turned portion 6 takes the place of a core as well as serving as a brace. The turns should 60 all be on a curve rather than angular but preferably the last upward turn 5 should be relatively short and the last outward turn 6, should be more nearly flat or only slightly curved and on a larger radius than the curve 65 of the upward turn 5, so that the portions 4 and 6 form an oval whose longer diameter is at right angles with the side of the body 1 of the can.

With the form of construction above described the mouth of the can is a smooth, outwardly rolling surface, there are no angular edges at the top, and there are no projections on the inner face of the can and no angular outside corners or edges and no raw 75 edges. The rim is integral with the body of the cylinder and strongly self braced, and the roll rim also serves as a convenient, smooth grip for lifting the can.

What I claim is:

A can having a cylindrical body, and an outwardly turned radial rim roll integral with said body and extending entirely around the periphery of the rim, said roll having an outwardly turned curved upper 80 portion, thence a downward turn curved on a shorter radius than the said outward turn, thence a turn toward the body curved on a greater radius than said downward bend and being substantially horizontal, thence an upward bend contacting with the body and on a shorter radius than said horizontal bend, thence another outward turn intermediate between said upper and lower turns and extending substantially in a horizontal 85 direction at right angles with the body and into contact with the inner face of the first mentioned downward portion of the roll.

In testimony whereof I affix my signature in presence of two witnesses.

PAUL I. ANDREWS.
